UNITED STATES PATENT OFFICE

WILLARD CHARLES FRENCH, OF GALT, ONTARIO, CANADA, ASSIGNOR, BY DIRECT AND MESNE ASSIGNMENTS, TO ROBERT CRAWFORD, OF ST. CATHARINES, ONTARIO, CANADA

SEPARABLE FASTENER

Application filed January 17, 1927. Serial No. 161,626.

The principal objects of the invention are, to produce a stringer on which are secured the individual interlocking members of a separable fastener, which will be uniformly strong throughout its entire length to hold the interlocking members securely and to retain its shape to keep the individual interlocking member in proper alignment, and to devise a stringer preferably in the form of a braid 10 which will be completed in one operation.

In carrying out the invention the body of the stringer is fabricated and longitudinal ribs are formed along one edge of each stringer, these ribs being opposite each other and 15 on opposite sides of the stringer. The ribs are formed by forming tubular pockets in which are introduced, as the stringer is fabricated, stuffers of the desired quality to assure the proper securing of the fastener elements. 20 The side ribs are preferably re-enforced by an intermediate rib between the side ribs.

In the accompanying drawings, Figure 1 is an elevational view of pieces of braid showing application to a separable fastener.

Figure 2 is an enlarged exaggerated perspective view of a piece of braid showing a metallic fastener member secured thereto.

Figure 3 is a plan diagram of the surface plate of a braider member designed for manufacturing my improved braid.

Figure 4 is a plan diagram of a modified arrangement of braider.

Figure 5 is an exaggerated sectional view of a braid constructed on the latter form of machine.

In the manufacture of what is known as a "separable fastener", a braid is used which has a beaded edge and the individual fastener members are secured to this beaded edge and 40 must retain alignment with each other, consequently the beads which are arranged on both sides of the braid must be uniform and strong.

In the manufacture of this type of fastener 45 it has been the practice to secure a pair of cords, one on each side of the braid by stitching same to the braid. This is a very expensive operation and more or less uncertain in regard to the location of the stitching through the cords. In the present invention

these ribs are formed coincidently with the fabrication of the stringer.

In the form illustrated in Figures 2 and 3 the braider spool carriers operate on the cam plate which has the interlacing grooves 55 for directing the carriers arranged in a substantially circular form, one end curving inwardly toward the centre.

As illustrated in this diagram, the main braid grooves A and B have the larger circular end C at one extremity and the larger circular guide groove D near the opposite end 60 preferably terminating near the vertical axis of the circular arrangement of grooves. The guide groove F is arranged in advance of the 65 circular guide groove D and is operatively connected therewith by guide grooves E and G at each side of the line of guide grooves.

The carriers of ordinary braider type travel in the paths indicated by the arrows from the 70 circle C around to the circle D. Meshing with the transfer wheels arranged below the cam plate of the machine are transfer wheels which take the spool carriers from the circle D at the point o on to the circle E, and the 75 carrier moving along the circle E is transferred at x to the circle F and from the circle F transferred across at o to the circle G and along the circle G back to the circle D from whence it travels back around the orbit of the 80 interlacing grooves of the cam plate.

Mounted in the circles G and E are carriers of ordinary braider type which alternate with the carriers coming from the circle D. The carrier X travelling around the 85 circle E is picked up at the point of intersection o with the circle D and following the direction of rotation of the gear of the circle D is carried along the circle D to the circle G where it is picked up at the point x and 90 carried around the circle G, being picked up at the point o by the circle F and passed along the circle F to the point of intersection with the circle E and transferred back to the circle E.

It will be readily understood from this description with a set of carriers circulating around the two circles E and G across the main line of the braid grooves between the 100

circles D and F by way of said circles D and F and alternating with carriers in the main line of braid grooves passing from the circle D to and around the circle F and returning to the circle D by way of the circles E and G, that there will be an interlacing of the threads in such a manner as to form pockets at each side of the main fabric made up of loops e and g. These loops formed by the carriers operating around the circles E and G are carried around and form pockets for stuffers of a suitable thickness and it is also preferable to arrange a stuffer in the pocket formed by loops f resulting from the circle F, though this latter stuffer is not desired to be as heavy as those in the loops formed by the circles E and G. Such stuffers are clearly illustrated at the ends of the series of loops or pockets e, g, and f in Fig. 2.

The braiding of the threads around the parallelly arranged stuffers in the manner described produces a braid with a pair of oppositely arranged ribs held securely in their position in relation to the main web of the braid by the stuffed end loop f.

The fastener members H which are of metal formed with a pair of prongs I embrace the ribbed edge of the braid, being pinched in around the back of the ribs E and G. These fastener members are spaced uniformly apart on the braid and grip the ribbed edge of the braid securely and the braided rib as described retains a straight longitudinal edge which holds all the fasteners in proper alignment.

Further, the ribs when braided in to the fabric have the maximum of strength and as they are formed in the braiding operation no further handling of the braid or of any other material is required between the construction of the braid and the application of the fastener members thereto.

It may be found desirable to produce a braid with a heavier ribbed edge than that which may be formed by single stuffers, such as are shown in the loops e and g and in Figure 4 is diagrammatically illustrated a different arrangement of a cam plate for forming a ribbed braid.

In this diagram the carriers passing from the loop J are carried partly around the loop K and transferred to the loop L and being carried partly around the loop L are transferred to the loop M which carries them around three-quarter's of a circle and transfers to the loop N. It then transfers to K and from K the carriers are transferred to the loop O and from O they pass to P which conducts them back to N and from N they are passed to M which transfers to L and from L to K, K to N; N to P and looping around P are picked up by O, transferred to K and back to J in the direction opposite to the commencement.

A strong heavy interlaced ribbed edge is thus formed.

It is of course understood that stuffers of any desirable weight may be introduced in the several loops formed by the interlacing carriers following around the loops from J to P and back again.

It must be understood that other arrangements of forming the loops may be devised to accomplish the fabricating into a fabric of stuffers disposed on opposite sides of a stringer in such a manner as to form a strong and straightly aligned support for the individual interlocking fastener members of a separable fastener.

What I claim as my invention is:

1. A braid for separable fasteners, comprising a braided web having threads looped to extend laterally therefrom forming tubular pockets at each side thereof said loops embracing longitudinal stuffers extending along opposite sides of the braid and directly opposite each other.

2. A braid for separable fasteners, comprising a braided web having a rib formed on one edge and projecting from each face thereof, and ribs formed thereon at both sides of the edge rib.

3. A braid for separable fasteners comprising a braided web having a stuffer incorporated into a central tubular pocket along one edge, and stuffers arranged on the opposite sides of said web against said pocket and enclosed by laterally extending tubular pockets.

4. A braid for separable fasteners comprising a braided web having a central rib along one edge formed by a stuffer incorporated into a central tubular pocket along one edge, and ribs extending longitudinally of the web arranged directly opposite each other and at each side of said pocket.

5. A braid for separable fasteners comprising a braided web having a central rib formed on one edge and projecting from each face thereof by a stuffer enclosed by threads looped therearound forming tubular pockets, longitudinal stuffers arranged on opposite sides of said central rib, and threads looped transversely across said web and embracing said longitudinal stuffers in tubular pockets formed by said transverse loops.

6. A stringer for separable fasteners comprising a fabricated textile web having threads looped to extend laterally therefrom along an edge and at each side thereof, said loops forming tubes and longitudinal stuffers arranged in said tubes.

7. A stringer for separable fasteners comprising a fabricated textile web having a central rib formed at one edge extending laterally from each face thereof, and ribs formed thereon at both sides of the central rib.

8. A stringer for separable fasteners com-

- prising a fabricated textile web having a stuffer incorporated into a central tubular pocket at one edge, and stuffers arranged along the edge on opposite sides of said pocket and enclosed by tubular extending pockets. 5
9. A stringer for separable fasteners comprising a fabricated textile web and stuffers arranged along an edge and at opposite sides of said web and threads looped transversely across said web to form tubes embracing said longitudinal stuffers. 10
10. The combination of a pair of stringers, each comprising a fabricated textile web having threads looped to extend laterally therefrom along an edge and at each side thereof, said loops forming tubes adjacent to the fastening edge thereof, longitudinal stuffers in said tubes and interlocking fastening members secured over the beaded edges formed by the loops and stuffers. 15
11. A stringer for separable fasteners comprising a fabricated textile web and oppositely disposed ribs comprising tubes fabricated with the web and longitudinal stuffers fabricated thereinto at one edge of the stringer, the thickness of the stringer laterally through the ribs being greater than the width of the stringer from the stringer edge to the rear of 20 the ribs. 30
12. A stringer for separable fasteners comprising a fabricated textile web having threads forming longitudinally extending tubes at each side along one edge thereof, and longitudinal stuffers arranged within said tubes, said stuffers extending said tubes to form laterally extending ribs at each side of the edge of the web. 35
13. A stringer for separable fasteners comprising a fabricated textile web having threads forming a central longitudinal tube along one edge and longitudinally extending tubes on opposite sides of the web, and stuffers arranged within said tubes and extending 40 said pockets, the tube at each side of the edge forming a longitudinally extending rib. 45
14. The combination of a pair of stringers, each comprising a fabricated web having threads forming longitudinally extending tubes at each side along one edge thereof, longitudinal stuffers arranged within said tubes, said stuffers extending said tubes to form laterally extending ribs at each side of the edge of the web, and interlocking 50 fastening members secured over the ribs formed by said tubes. 55
15. A stringer for separable fasteners comprising a braided web having threads forming longitudinally extending tubes at each side along one edge thereof, and longitudinal stuffers arranged within said tubes, opposite stuffers extending said tubes to form laterally extending ribs at each side of the edge of the web. 60
16. A stringer for separable fasteners com- 65
- prising a braided web having threads forming a central longitudinal tube along one edge and longitudinally extending tubes on opposite sides of the central tube, and stuffers arranged within said tubes and extending 70 said tubes, the tube at each side of the edge forming a laterally extending rib. 75
17. The combination of a pair of stringers, each comprising a braided web having threads forming longitudinally extending tubes at each side along one edge thereof, longitudinal stuffers arranged within said tubes, opposing stuffers extending said tubes to form laterally extending ribs at each side of the edge of the web, and interlocking fastening members 80 secured over the ribs formed by said tubes. 85
18. A stringer for separable fasteners comprising a fabricated textile web having threads forming a plurality of adjacent tubes on each side of the web adjacent to an edge thereof and stuffers arranged in said tubes extending the same and forming ribs along each side of the web. 90
19. A stringer for separable fasteners comprising a fabricated textile web having a central tube along the edge thereof and a plurality of adjacent laterally extending tubes on each side of the web adjacent to the edge; and stuffers in opposing tubes and extending the same, the plural tubes forming 95 ribs along each side of the web adjacent to its edge. 95
20. The combination of a pair of stringers, each comprising a fabricated web having threads forming a plurality of laterally extending tubes at each side of the web adjacent to each other and to the edge of the web; stuffers arranged in said tubes extending opposing tubes to form ribs along each side of the edge of the web; and interlocking fastening members secured over the ribs thus formed. 100 105
21. A stringer for separable fasteners comprising a braided web having threads forming a plurality of laterally extending tubes at each side of the web adjacent to its edge; and stuffers arranged in opposing tubes, extending the same and forming laterally extending ribs at each side of the web along the edge thereof. 110
22. A stringer for separable fasteners comprising a braided web having a central tube along its edge; a plurality of laterally extending tubes at each side of the web adjacent its edge; and stuffers in opposing tubes extending said tubes to form laterally extending ribs 115 at each side of the web at the edge thereof. 120
23. A braid for separable fasteners comprising a braided web having threads looped to extend laterally therefrom forming tubular pockets at each side thereof, stuffers extending longitudinally along each side of the braid and opposite each other and embraced by said loops, the same threads forming the web and the loops embracing the longitudinal stuffers. 125 130

24. A stringer for separable fasteners comprising a braided web having threads forming longitudinally extending tubes at each side along one edge thereof, and longitudinal stuffers arranged within opposing tubes, said stuffers extending said tubes to form laterally extending ribs at each side of the edge of the web, the same threads forming the web and tubes. 70
- 10 25. A stringer for separable fasteners comprising a braided web having threads forming a central longitudinal tube along one edge and longitudinally extending tubes on opposite sides of the web adjacent to said edge, and stuffers arranged within said opposing tubes and extending said tubes, the tube at each side of the edge forming a laterally extending rib, the same threads forming the web and tubes. 75
- 15 26. The combination of a pair of stringers, each comprising a braided web having threads forming longitudinally extending tubes at each side along one edge thereof, longitudinal stuffers arranged within said tubes, said stuffers extending said tubes to form laterally extending ribs at each side of the edge of the web, the same threads forming the web and tubes, and interlocking fastening means secured over the ribs formed by said tubes. 80
- 20 27. A stringer for separable fasteners comprising a braided web having threads forming a plurality of laterally extending tubes at each side of the web adjacent to its edge; and stuffers arranged in opposing tubes, extending the same and forming laterally extending ribs at each side of the web along the edge thereof, the same threads forming the web and tubes. 85
- 25 28. A stringer for separable fasteners comprising a braided web having a central pocket along its edge; a plurality of laterally extending tubes at each side of the web along said edge; and stuffers in opposing tubes extending said tubes to form laterally extending ribs at each side of the web at the edge thereof, the same threads forming the web and tubes. 90
- 30 29. A stringer for separable fasteners comprising a braided web having threads forming a plurality of laterally extending tubes at each side of the web adjacent to its edge; and a stuffer arranged in a tube on each side, extending the same and forming a laterally extending rib at each side of the web along the edge thereof. 95
- 35 30. A stringer for separable fasteners comprising a braided web having a central tube along its edge; a plurality of laterally extending tubes at each side of the web along its edge; and a stuffer in a tube on each side extending said tubes to form a laterally extending rib at each side of the web at the edge thereof. 100
- 40 31. A braid comprising a braided web hav- 105
